Inventor:

E. T. Stover

UNITED STATES PATENT OFFICE.

EVAN T. STOVER, OF CHICAGO, ILLINOIS, ASSIGNOR TO JOSEPH STOVER
AND GEORGE W. ROBERTS, BOTH OF SAME PLACE.

FACE-PROTECTOR.

SPECIFICATION forming part of Letters Patent No. 331,339, dated December 1, 1885.

Application filed November 10, 1884. Serial No. 147,473. (No model.)

To all whom it may concern:

Be it known that I, EVAN T. STOVER, residing at Chicago, in the county of Cook and State of Illinois, and a citizen of the United States, have invented a new and useful Improvement in Face-Protectors, of which the following is a full description, reference being had to the accompanying drawings, in which—

10 Figure 1 is a plan, and Fig. 2 a section at line *x* of Fig. 1.

The chief object of my invention is to provide a face-protector for use in cold weather, having a suitable portion made of transparent material, so that the features of the wearer can be seen. Other objects are to combine, with such face-protector, protection for the ears, to take the place of ear-muffs, and also to provide one or more openings for the eyes, covered with suitable material to afford reasonable protection against dust and snow, which objects I accomplish as illustrated in the drawings.

15 In the drawings, A represents a piece of suitable flexible material, preferably rubber cloth, of suitable size to cover the face of the wearer. As shown, each side is provided with an extension, *a*, large enough to cover the ears. The central portion of this rubber cloth is cut away, leaving a large opening, the upper portion of which should be arranged so as to come over the eyes of the wearer, and this portion I cover with fine wire-cloth *b*. The remainder of this opening is covered by a piece of mica, *c*.

20 The wire cloth and the mica can be conveniently secured to A by means of metal bands *d e*, one upon the outside and the other upon the inside of A, between which the edges 25 around the opening and the mica and the wire-cloth can be secured in place either by rivets or by prongs upon one of the bands made to pass through A and clasp over the other metal band.

25 *f* is a strip of metal, which is, as shown, made integral with the band *d*, extending from one side to the other at the point where the upper edge of the mica and the lower edge of the wire-cloth come together, and there is a 30 similar strip of metal connected with the inner band, *e*.

The protector may be provided with an

opening for the mouth, with a flap, *i*, extending over the same, as shown in the drawings; or the flap may be omitted, as well as the 35 opening for the mouth, if desired.

If desired, a small opening may be made in the part *a*, and be covered with fine wire-netting to facilitate hearing.

I thus provide a face-protector which does 40 not completely conceal the features of the wearer, the same being provided with a large opening covered with a transparent material. I use mica preferably, because it is less liable to break than any other transparent material 45 of which I have knowledge.

While my protector is primarily designed to be used in cold weather, it may be used for some other purposes to which it is adapted. The wire-gauze over the opening for the eyes 50 will effectually protect the same against dust and snow.

Mica might be used over the eyes, instead of wire-cloth; but it is desirable to have some ventilation, and the wire-cloth provides 55 part for that.

This protector, being made of flexible material, can be folded in a comparatively small compass, and carried, if desired, in a suitable 60 pocket or receptacle provided therefor.

The article can be secured on the head by suitable straps, (not shown in the drawings.)

As shown, the piece A is provided with a lining, *h*, which may be made of flannel or other suitable cloth.

What I claim as new, and desire to secure by Letters Patent, is—

1. A face-protector consisting of a flexible piece, A, having extensions *a* to cover the ears, and provided with one or more openings 70 for the eyes, and with a central opening below the line of the eyes, covered by a transparent piece, *c*, substantially as and for the purpose specified.

2. A face-protector consisting of a flexible piece, A, provided with one or more openings 75 for the eyes, protected by wire-gauze *b*, in combination with a central transparent piece, *c*, over an opening in A, substantially as and for the purposes specified.

EVAN T. STOVER.
